UNITED STATES PATENT OFFICE.

STERLING H. CAMPBELL, OF ST. LOUIS, MISSOURI.

COUPLING-RELEASE RIGGING.

Application filed May 27, 1921, Serial No. 473,142. Renewed March 5, 1923.

To all whom it may concern:

Be it known that I, STERLING H. CAMPBELL, a citizen of the United States of America, residing at the city of St. Louis, State of Missouri, United States of America, have invented a certain new and useful Coupling-Release Rigging, of which the following is such a full, clear, and exact description as will enable any one skilled in the art to which it appertains to make and use the same, reference being had to the accompanying drawings, forming part of this specification.

My invention relates to a coupler release rigging of that type in which a single connecting member extends between the operating arm and the coupler locking pin. The object of my invention is to produce a simple and strong device of the class referred to in which the connecting member may be formed from a piece of square or round stock, preferably the former, by bending operations alone and in which the eye end of the operating lever may be formed by drop forging.

In the accompanying drawings which illustrate one form of device made in accordance with my invention together with a portion of the railway car to which the same is applied, Figure 1 is a plan view on a reduced scale, Figure 2 is a plan view of the end of the operating lever and connecting stirrup, Figure 3 is a front view of the parts shown in Figure 2, and Figure 4 is a side view of the parts shown in Figures 2 and 3, the stirrup being shown in engagement with the eye of the coupler locking pin.

5 indicates a railway car provided with a coupler 6 having the usual locking pin 7. 8 is a rock shaft suitably secured to the end of the car 5 and provided with a forwardly extending operating lever 9 terminating in the flattened end 10. The end 10 is provided with a central part or member 11 adapted to pass between the arms of the connecting stirrup, as will be hereinafter set forth. 12 and 13 are front and rear transverse portions, respectively, the ends of which portions carry side bars 14 which preferably extend entirely across the space between the parts 12 and 13 so as to form two complete vertical eyes 15. These eyes 15 are adapted to receive the arms 16 of the stirrup, the lower portion 17 of which 55 is formed into an elongated loop adapted to pass through the eye of the coupler lock-

ing pin 7 as shown in Figure 4. The upper ends of the arms 16 terminate in curved portions 18 bent at right angles to the body of the stirrup and adapted to engage with either the front transverse bar 12 or the rear transverse bar 13, preferably the former as shown in Figures 2 and 4 of the drawings.

Owing to the form of my stirrup it can be readily formed by simple bending operations from either round or square stock, I prefer to use the latter for the reason that greater strength can be obtained from equal amounts of metal by using square stock and, furthermore, the bending operations are more easily performed on square than on round stock. The double form of eye used in the end of the operating lever enables the use of a strong construction which can be readily formed by drop forging owing to the comparatively small amount of material which must be forced laterally. As the side bars 14 serve merely to prevent the spreading of the arms 16 they may be made comparatively thin.

Having fully described my invention, what I claim as new and desire to secure by Letters Patent of the United States is:

1. In a device of the class described, the combination with a coupler locking pin, of an operating lever therefor having a laterally extending integral portion, and a stirrup passing through the eye of the locking pin and provided with a pair of arms having their ends bent in a plane substantially at right angles to the plane of the stirrup and engaging with the laterally extending integral portion of the operating arm to lift the locking pin.

2. In a device of the class described, the combination with a coupler locking pin, of an operating lever therefor having a laterally extending integral portion, and a stirrup passing through the eye of the locking pin and provided with a pair of arms having their ends curved in a plane substantially at right angles to the plane of the stirrup body and in engagement with the laterally extending integral portion of the operating arm to lift the locking pin.

3. In a device of the class described, the combination with a coupler locking pin of an operating lever therefor, and a stirrup passing through the eye of the locking pin, the ends of said stirrup forming a pair of upwardly extending arms, said operating lever having a central portion extending be-

tween the arms of the stirrup, front and rear transverse portions limiting the movement of said arms, and means for preventing the disengagement of the stirrup from the operating lever when the parts are in position on the car.

4. In a device of the class described, the combination with a coupler locking pin, of an operating arm therefor, a stirrup passing through the eye of the locking pin and having a pair of upwardly extended arms, said operating lever having a central portion extending between the arms of the stirrup, front and rear transverse portions for limiting the movement of said arms, and means for preventing the disengagement of the stirrup from the operating lever when the parts are in position on the car, said operating lever being also provided with means for preventing the spreading of the stirrup arms.

5. In a device of the class described, the

combination with a coupler locking pin, of an operating lever therefor, said lever being provided with a pair of vertical eyes, 25 and a stirrup passing through the eye of the locking pin and provided with a pair of arms, one passing through each eye of the operating lever, and means carried by said arms and engaging with the operating lever to lift the pin.

6. In a device of the class described, the combination with a coupler locking pin, of an operating lever therefor, said lever being provided with a pair of vertical eyes, and a 35 stirrup passing through the eye of the locking pin and provided with a pair of arms, one passing through each eye of the operating lever, the ends of the said arms being bent at substantially right angles to the 40 plane of the stirrup body.

In testimony whereof, I have hereunto set my hand and affixed my seal.

STERLING H. CAMPBELL. [I.S.]
